UNITED STATES PATENT OFFICE.

FRANK R. CHAPMAN, OF GREENFIELD, MASSACHUSETTS.

DESIGN FOR A HANDLE AND BOLSTER FOR TABLE CUTLERY.

Specification forming part of Design No. 5,102, dated July 11, 1871.

To all whom it may concern:

Be it known that I, FRANK R. CHAPMAN, of Greenfield, in the county of Franklin and State of Massachusetts, have invented and produced a new and original Design for Table-Knife and Fork-Bolsters and Handles; and I do hereby declare the following to be a full, clear, and exact description of the same, reference being had to the accompanying drawings making a part of this specification, in which the figure is a perspective view of a knife illustrating my invention.

This design consists of grooves *a a* and *d d*, made lengthwise in each side of the bolster A and handle B of a knife or fork, next to the edges of said bolster and handle, the grooves in the former running into those in the latter, and the grooves *d* in each side meeting at the butt of the handle; also, of a wider groove, *b*, made lengthwise in each side of the bolster between

the grooves *a*, this groove being slightly tapering, and also of a groove, *c*, made lengthwise of each side of the handle, between the grooves *d*, said groove forming a combination of the groove *b*, and also tapering and finally running out, all its lines converging to a common point, *f*, in the handle.

What I claim as my invention, for a design is—

1. The grooves *a b* in the bolster A, as specified.
2. The combination of the grooves *a b* of the bolster with the grooves *c d* in the handle, as described.

FRANK R. CHAPMAN.
